LOCK SET HANDLE

John Axel Tor noe and Robert Anthony Marotto, Redwood City, Calif., assignors to Schlage Lock Company

Filed Feb. 22, 1971, Ser. No. 117,875

Term of patent 14 years

Int. Cl. D8—06

U.S. Cl. D8—138

FIG. 1 is a front elevation of a lock set handle, showing the new design;

FIG. 2 is an elevation from one side of the article of FIG. 1;

FIG. 3 is an elevation from the opposite side of the article of FIG. 1;

FIG. 4 is a rear elevation of the article of FIG. 1;

FIG. 5 is an elevation from one end of the article of FIG. 1; and

FIG. 6 is an elevation from the opposite end of the article of FIG. 1.

We claim:

The ornamental design for a lock set handle, as shown.
